UNITED STATES PATENT OFFICE.

ELIJAH H. DANIELS, OF CHICAGO, ILLINOIS.

STOVE-PIPE SHELF.

SPECIFICATION forming part of Letters Patent No. 363,809, dated May 31, 1887.

Application filed November 23, 1886. Serial No. 219,658. (No model.)

To all whom it may concern:

Be it known that I, ELIJAH H. DANIELS, a citizen of the United States, residing at Chicago, in the county of Cook and State of Illinois, have invented certain new and useful Improvements in a Stove-Pipe Warming Shelf and Oven, of which the following is a full and complete specification.

The object of my invention is to obtain a light and easily-constructed warming shelf, or warming shelf and oven, suitable to attach to the pipe of an ordinary stove, either kitchen or parlor stove, for the purpose of keeping articles placed thereon or therein warm for any desired period of time.

I have illustrated my invention by the drawings accompanying this specification, in which—

Figure 1 is a front elevation of my invention, and Fig. 2 is a sectional view of the same.

Like letters refer to like parts throughout the several views.

X is a stove-pipe to which my invention is attached. I prefer to construct my warming shelf and oven with pipe X placed therein, and in applying the device to stoves already in use it is merely necessary to take out from the pipe of said stove a piece of the pipe of equal length with pipe X.

Y is an ordinary damper, as is also Z.

A A' A" are holes or perforations in pipe X.

B is an ordinary pipe or flue leading from hole A in pipe X to hollow C' of the shelf C.

B' is a pipe or flue communicating by hole

A' with pipe X and the hollow space D' around oven D.

b is a sleeve or collar around pipe X.

The warming shelf and oven may be rotated around the pipe X, if desired, turning upon

collar b and that portion of the warming-shelf C inclosing said pipe. If it be not desired to

rotate the device around the pipe X, collar b may be dispensed with, and pipes or flues B B' attached directly to pipe X. When the

device is made so that it may be turned around pipe X, it will be perceived that collar b shuts off all communication between pipe X and the pipes B B', and also the outer or surrounding air.

The manner of operation of my invention is

as follows: Damper Y is turned to the position illustrated in Fig. 2, and the direct ascent of the smoke from the stove through pipe X is prevented, and thereby deflected through and into pipes B B', that portion of the smoke entering pipe B ascending into hollow C' in warming-shelf C, thereby warming said shelf, and, after passing through hollow C', re-entering pipe X through hole A". That portion of said smoke passing into and through pipe B' enters space D', and, passing around oven D, also enters pipe X through hole A". Free passage for the smoke in pipe X being afforded in the manner last above described but little effect is produced by the deflection of such smoke upon the draft of the stove or pipe X, and in order to control the draft of the stove by damper Y the warming shelf and oven must be turned one-quarter around from the positions illustrated, thereby cutting off the supply of heated smoke from both shelf and oven, and damper Z is therefore placed in pipe X, by which the draft of the stove to which my device is attached may be controlled during the time such smoke is deflected through said device.

Having thus described my invention and its manner of operation, what I claim, and desire to secure by Letters Patent, is—

1. In a stove-pipe warming shelf and oven, the combination of movable hollow shelf C and pipe B and pipe X, having holes A and A" and damper Y therein, all substantially as described, and for the purpose set forth.

2. In a stove-pipe warming shelf and oven, the combination of movable hollow shelf C and pipe B and pipe X, having holes A and A" and dampers Y and Z therein, all substantially as described, and for the purpose set forth.

3. In a stove-pipe warming shelf and oven, the combination of movable hollow oven D and pipe B' and pipe X, having holes A' and A" and damper Y therein, all substantially as described, and for the purpose set forth.

4. In a stove-pipe warming shelf and oven, the combination of hollow oven D, pipe B', and pipe X, having holes A' A" and dampers Y and Z therein, all substantially as described, and for the purpose set forth.

5. In a stove-pipe warming shelf and oven, the combination of hollow shelf C, pipe B, hollow oven D, pipe B', and pipe X, having holes A A' A'' and damper Y therein, all substantially as described, and for the purpose set forth.
6. In a stove-pipe warming shelf and oven, the combination of hollow shelf C, pipe B, hollow oven D, pipe B', and pipe X, having holes A A' A'' and dampers Y and Z therein, all substantially as described, and for the purpose set forth.
7. In a stove-pipe warming shelf and oven, the combination of hollow shelf C, pipes B B', hollow oven D, collar b, and pipe X, having 15 holes A, A', and A'' and damper Y therein, all substantially as described, and for the purpose set forth.
8. In a stove-pipe warming shelf and oven, the combination of hollow shelf C, pipes B B', hollow oven D, collar b, and pipe X, having 20 holes A, A', A'' and dampers Y and Z therein, all substantially as described, and for the purpose set forth.
